UNITED STATES PATENT OFFICE.

BENJAMIN L. SEVERANCE, OF EAST JORDAN, MICHIGAN

FOLDABLE BOX OR RECEPTACLE.

Application filed June 22, 1921. Serial No. 479,626.

To all whom it may concern.:

Be it known that I, BENJAMIN L. SEVERANCE, a citizen of the United States, residing at East Jordan, in the county of Charlevoix and State of Michigan, have invented certain new and useful Improvements in Foldable Boxes or Receptacles, of which the following is a specification.

This invention relates to improvements in what may be termed knock-down or foldable boxes or receptacles, which may be equally applicable to crates.

The invention has for its object mainly to simplify and expedite the construction of the box or crate, as in the manufacture thereof at the factory, also to greatly facilitate and expedite the assembling of the parts of the box or crate in receiving the same in its knock-down condition.

A further object of my invention is to provide for carrying out the foregoing purposes or ends in a simple, expeditious, effective and inexpensive manner.

Other objects of the invention, together with the foregoing, will be apparent from the following description of the construction, arrangement and application of the same.

The invention therefore consists of certain instrumentalities and features of construction substantially as hereinafter more fully set forth and pointed out in the appended claims.

The accompanying drawings illustrate the preferred embodiment, or one form, of my invention wherein it will be understood that various changes and modifications as relate to the detailed construction and arrangement of parts may be made without departing from the spirit or scope of my invention covered by the claims, and in which drawings—

Figure 1 is a view in perspective showing the several parts of my knock-down or foldable box or crate in extended condition.

Fig. 2 is also a perspective view of the same showing the stage of joining the parts.

Fig. 3 is a similar view showing the parts of the box or crate completely assembled as in use.

In carrying out my invention, I provide the principal elements of a bottom 1, sides 2, ends 3 and a top or closure 4, these being formed in the usual outline, according as may be desired to form a closed receptacle or crate. The bottom and sides have suitably

applied and secured thereto along their opposed edges, bars 5, which bars are provided with longitudinal grooves 5^a and 5^b, inwardly from the sides, adapted to receive the ends at their vertical and horizontal edges, respectively. These bars or transverse members are provided at their ends with dovetail tenons or tongues, and mortises 6 and 6^a, said tongues being bifurcated and received by said mortises to effect an interlocking action therebetween at those points. Likewise the ends 3 have also applied thereto at their top or upper edges bars 7 having longitudinal grooves 7^a receiving said ends at their upper edges, all of the parts, having been disposed and properly forced together will, thus assembled, form the complete enclosure or crate as shown. The sides, it will be observed, are bound or secured to the bottom, by means of preferably four pieces of strap-metal 8 suitably secured or nailed thereto from the outside and the other parts of the box or crate are effectively retained in place by suitably nailing the same at the four top corners, as at 9.

As has been previously indicated, my box or crate-forming enclosure, being of the knock-down type, has its several parts adapted to be readily and compactly placed for convenient shipment from the factory to packers or those receiving the same, as farmers, or others, who may have use therefor, and also is readily adapted to provide for facility in assembling the parts of the enclosure or crate by the packer upon receiving it from the factory. It is also observed that the device is exceedingly simple, light and inexpensive.

I claim:—

1. A knock-down or foldable receptacle, including ends, sides, and a bottom, said sides and bottom being provided with transverse members, said transverse members being adapted to receive the lateral and bottom edges of said ends, and having an interlocking connection at their ends, said interlocking connection being formed of bifurcated or forked tenons at opposite ends of certain transverse members, and slots or mortises in the ends of abutting transverse members receiving said tenons.

2. A knock-down or foldable receptacle, including ends, sides, and a bottom, said sides and bottom being provided with transverse members, said transverse members being provided with longitudinal grooves

adapted to receive the lateral and bottom edges of said ends, and having interlocking connections, said interlocking connections being formed of bifurcated or forked tenons at opposite ends of certain transverse members, and slots or mortises in the ends of abutting transverse members receiving said tenons.

3. A knock-down or foldable receptacle, including ends, sides, a bottom, and a closure, said bottom and sides being provided with transverse members having grooves receiving the lateral and bottom

edges of said ends, and a pair of transverse members having longitudinal grooves receiving the top edges of said ends and adapted to be interlocked with the transverse members of the sides, the interlocking connection being formed of bifurcated or forked tenons at the opposite ends of certain transverse members, and slots or mortises in the ends of abutting transverse members receiving said tenons.

In testimony whereof I affix my signature.

BENJ. L. SEVERANCE.
